Primary Examiner — Selina Sikder(74) *Attorney, Agent, or Firm* — Procopio, Cory, Hargreaves & Savitch LLP**CLAIM**

The ornamental design for a light emitting diode, as shown and described.

DESCRIPTION

FIG. 1 is a perspective view of an embodiment of a light emitting diode showing our new design;

FIG. 2 is a top plan view thereof;

FIG. 3 is a front view thereof;

FIG. 4 is a rear view thereof;

FIG. 5 is a left side elevational view thereof;

FIG. 6 is a right side elevational view thereof; and,

FIG. 7 is a bottom plan view thereof.

The broken lines in the drawings depict portions of the light emitting diode that form no part of the claimed design. The broken lines immediately adjacent to the shaded surfaces form a boundary of the claim.
